[57] CLAIM

The ornamental design for a golf putter head, as shown and described.

DESCRIPTION

FIG. 1 is an isometric view of a golf putter head showing my new design with a portion of its shaft shown in phantom;

FIG. 2 is a top plan view;

FIG. 3 is a front plan view;

FIG. 4 is a rear plan view; and,

FIG. 5 is a side elevational view thereof.

The broken line showing of a fragmented shaft is for illustrative purposes only and forms no part of the claimed design.
